BURN-OFF MACHINE

Thomas W. Bailey, Hammondsport, N. Y., assignor to Corning Glass Works, Corning, N. Y., a corporation of New York

Application May 7, 1949, Serial No. 91,915

11 Claims. (Cl. 49—50)

1

The present invention relates to improvements in devices for severing glass by burning it off, and more particularly to devices in which the glass and burner travel in a circular path while the burning off is being accomplished.

The prime object of the invention is an improved form of apparatus for controlling the connection and disconnection of a source of vacuum-to-vacuum chucks employed in holding the ware during the burn-off operation and for controlling the connection and disconnection of fuel to the burn-off burners.

The invention is embodied in a machine wherein a cam opens a valve to apply vacuum from a suitable supply line to an article chuck as it passes through a loading zone and wherein the holding of such valve in its open position as the chuck leaves the loading zone is contingent on the presence of an article in the chuck so that if the chuck is unoccupied upon leaving the loading zone, the vacuum valve is closed and thus unnecessary opening of the vacuum supply line to atmosphere is prevented. As the chuck leaves the loading zone and enters the burn-off zone, cam means is provided for opening a valve in the fuel line to the burner associated with such chuck. Facilities are provided, however, to prevent such valve being opened if the chuck upon leaving the loading zone is unoccupied so that the connection of fuel to a burner associated with an unoccupied chuck is prevented.

The accompanying drawings show a preferred embodiment of the invention. In the drawings, Fig. 1 is a sectional side elevation of the machine; Fig. 2 is an enlarged sectional plan view of a fragment of the machine as indicated by line 2—2 in Fig. 1; Fig. 3 is a sectional elevation taken on line 3—3 in Fig. 2, and in addition, showing a sectional elevation of an associated burner not shown in Fig. 2; Fig. 3a is an enlarged sectional view of a fragment of an upper section of the apparatus shown in Fig. 3; Fig. 4 is a sectional plan view taken on line 4—4 of Fig. 3; Fig. 5 is a diagrammatic plan view illustrating the cam arrangement employed; Fig. 6 is an enlarged view in section of a vacuum valve assembly shown in its operated position and is similar to the view of such assembly appearing in the right-hand portion of Fig. 1 in its normal position; Fig. 7 is a sectional plan view taken on line 7—7 of Fig. 6; and Fig. 8 is an end elevation taken on line 8—8 of Fig. 2.

Referring now to the drawings in detail, the machine embodies a base 11 in which is mounted a central supporting column 12, adapted to be

rotated by a gear 13 in mesh with a driving pinion 14 carried by a shaft 15 rotatable by a motor (not shown). The upper portion of column 12 has secured thereto a turret 21 having arranged about 5 its periphery a number of brackets such as a bracket 22, each supporting an article chuck such as article chuck 23. Also arranged on column 12 is a vacuum chamber 31 having attached thereto a manifold 32 containing an annular oxygen chamber 33 and an annular gas chamber 34. The chamber 31 on its underside near its periphery is provided with a vacuum control valve assembly such as the assembly 51, (Figs. 1 and 6) for each chuck assembly. The 10 chamber 31 also is provided about its periphery with brackets such as 41, (Figs. 1 and 3) each provided with a burner supporting bracket 42 and a burner 43. Each bracket 41 also supports burner control valves and their operating mechanisms, as will be described hereinafter.

Vacuum control valve

Referring particularly to Fig. 6, each of the 25 vacuum control valves such as valve 51, is secured to the underside of vacuum chamber 31 by a cap screw 52, and has a chamber 53 in communication therewith by way of suitable passages 54. The chamber 53 also communicates with a valve chamber 55 by way of a passage 56 normally closed by a disc member 57 carried by a valve 30 stem 59 and held against an associated seat 58 by a spring 60.

With the valve disc 57 on its seat 58, chamber 35 55 is in communication with atmosphere by way 35 of a passage between a valve member 72 and its seat 74 through an exhaust passage 71. The chamber 55 is also in communication by way of a conduit 73 with a vacuum chuck such as chuck 23, and by way of a conduit 129 with a negative 40 pressure chamber (not shown) similar to chamber 121 (Figs. 1 and 3). The valve 51 has an additional chamber 75 in communication with the chuck 23 by means of a conduit 76 extending from the chamber wall 70.

45 The valve actuating stem 59 is at one end provided with a cross arm 77 (Figs. 6 and 7) carrying a roller 79 adapted to engage a cam 80 to move the stem from its normal position shown in Fig. 1 to its operated position shown in Fig. 6 50 as the chuck 23, associated with valve 51, enters the loading zone. With valve 51 in its operated position the valve member 72 is on its seat 74 so that the chamber 55 is closed to atmosphere and vacuum chamber 31 is in communication with 55 chuck 23 via conduit 73, chamber 55, passage 56,

chamber 53, and passages 54. Accordingly, a piece of glassware placed in the chuck will be retained therein by vacuum.

One wall of chamber 75 comprises a diaphragm 78 attached to stem 59. By cutting off the inflow of air into the chuck 23 by placing an article therein, the negative pressure in chamber 75 is sufficiently increased to hold the diaphragm 78 and with it stem 59 in their operated position so that, as the chuck passes out of the loading zone into the burn-off zone, the valve 51 will remain operated even though roller 79 moves off the lobe of cam 80. If, on the other hand, the chuck is not loaded while passing through the loading zone, the negative pressure in chamber 75 will be insufficient to hold the stem 59 in its operated position and accordingly, as the chuck 23 leaves the loading zone, the stem will be restored to its normal position by spring 60 to reclose the passage 56 and thus prevent unnecessary admission of air into the vacuum chamber 31.

Burner control valve

For each burner such as burner 43 (Fig. 3) there is an oxygen line 91 (Figs. 1 and 2) extending from oxygen chamber 33 to a manually operable valve 94 which feeds oxygen through a spring-closed valve 95 to a mixing chamber 100 (Fig. 8). A similar line 98 extends from gas chamber 34 to a manually operable valve 99 for feeding gas through a spring-closed valve 96 to the mixing chamber 100. A passage 105 extends from mixing chamber 100 through a flexible tube 106 to the burner 43.

Valves 95 and 96 are adapted to be opened by adjustable cap screws 109 and 110, threaded through a lever 111 which at the one end is pivoted on a pin 112, and at the other end is coupled to a slide rod 113. The rod 113, having reference to Figs. 2 and 3a, is adapted to be moved to the right, to open the valves 95 and 96, by an arm 115 integral with a sleeve 118 splined to an extension 116 attached to the upper end of a rock shaft 117. The bottom end of shaft 117 carries a rocker arm 119, having a spring 119a on one end tending to rock the shaft clockwise, and a cam roller 120 on its other end adapted to encounter a cam 121 as its associated chuck 23' (Fig. 1) leaves the loading zone, to rock the shaft in a counterclockwise direction to open valves 95 and 96.

The normal position of arm 115, however, as indicated in Fig. 3a, is at a level below that of slide rod 113, so that unless arm 115 is in its raised position at the time that roller 120 engages cam 121, opening of valves 95 and 96 will not occur. The sleeve 118, with which arm 115 is integral, is supported on a stem 125 attached to a diaphragm 126 forming a wall of negative pressure chamber 127. A spring 128 assists gravity in normally holding sleeve 118 in its lower position. Chamber 127 is connected by means of a conduit 129 with a chamber of valve 51' corresponding to chamber 55 of valve 51.

It accordingly follows that sufficient negative pressure will not be built up in chamber 127 to raise sleeve 118 unless there is an article in the chuck 23'. As will be understood, with an article in chuck 23', the arm 115 of sleeve 118 will have been brought into alignment with slide rod 113 while the chuck was passing through the loading zone. Under these circumstances engagement of the cam 121 by its roller 120 upon entering the burn-off zone opens valves 95 and 96 to supply fuel to burner 43. A suitable pilot light 130 ar-

ranged at the junction of the loading and burn-off zones lights the burner.

As a chuck, chuck 23' for example, leaves the burn-off zone, roller 120 passes off the lobe of cam 121 enabling spring 119a to rock shaft 117 to its initial position, thus permitting valves 95 and 96 to reclose and cut off the fuel supply to burner 43.

As a chuck, chuck 23 for example, enters the unloading zone, roller 79 of the associated valve 51 engages a cam 140 which, in spite of the negative pressure in chamber 75, restores the stem of valve 51 to its normal position to cut off the vacuum to chuck 23 and to at the same time vent the chuck to atmosphere so as to release an article, such as article 150, for example, from the chuck. The restoration of valve 51 to normal in venting chuck 23 to atmosphere also vents chamber 75 and the corresponding chamber 127. With chamber 75 vented, valve 51 will not operate again until its roller 79 again encounters cam 80. The venting of the chamber corresponding to chamber 127 enables the associated elements, not shown but corresponding to sleeve 118 and its arm 115, to be restored to their initial position by a spring such as spring 128.

Auxiliary features

In order to positively assure closure of valve disc 51 on its seat 56 by cam 140, and the seating of the other similar valve discs on their seats without necessitating extreme precision in manufacture, such cam is carried by a spring-loaded bell crank 151 (Fig. 1) which enables movement of the cam following engagement of a disc member such as 57 with its seat. In a similar fashion positive closure of each valve member such as member 72 on its seat by cam 80 is assured by placing the pivot 152 of cross arm 77 (Fig. 7) in a slot 153 and normally resiliently holding pivot 152 at the right end of the slot by a spring 154. With this arrangement any movement imparted to a cross arm 77 by cam 80 after member 72 is seated simply causes the pivot 152 of arm 77 to shift leftward (see Fig. 7) against the tension of spring 154.

What is claimed is:

1. In a burn-off machine, a vacuum article chuck, means providing a path of travel for said chuck through loading and burn-off zones, respectively, a vacuum line to said chuck, a normally closed valve in said vacuum line, means for opening said valve when said chuck enters the loading zone and for holding said valve open only while the chuck is passing through such zone, means activated by the creation of negative pressure in the branch of said line between said valve and said chuck when an article is engaged by said chuck to continue to hold said valve open through the burn-off zone, a burner associated with said chuck, a fuel line to said burner, a normally closed valve in said latter fuel line, an element for opening said latter valve, said element being normally inoperatively associated with respect to said latter valve, other means operative only upon the creation of such negative pressure to bring said latter valve and element into operative association, and means for moving said element with respect to said latter valve to open the same as the chuck enters the burn-off zone.
2. In a burn-off machine, an article chuck, means providing a path of travel for said chuck through loading and burn-off zones, respectively, a burner associated with said chuck, a fuel line

to said burner, a normally closed valve in said fuel line, an element for opening said valve, said element being normally inoperatively associated with respect to said valve, means operative pneumatically only when an article is engaged by the chuck to bring said valve and element into operative association, and means for moving said element with respect to said valve to open the same as the chuck enters the burn-off zone.

3. In an article-handling system, a vacuum article chuck, means providing a path of travel for said chuck through at least two zones, a vacuum line to said chuck, a normally closed valve in said vacuum line, means for opening said valve when said chuck enters the first of said zones and for holding said valve open only while the chuck is passing through such zone, and pneumatic means for continuing to hold said valve open through the second of said zones, independently of said valve-opening means, when an article is engaged by said chuck, said pneumatic means including a diaphragm associated with said valve and adapted to be moved from a normal to an operated position when said valve is opened, said diaphragm constituting one wall of a negative pressure chamber, and a branch vacuum line extending between said chamber and said first vacuum line between the article chuck and the valve.

4. In an article-treating machine, a rotary turret, a vacuum chuck carried by said turret, a vacuum line to said chuck, a line for supplying fluid in the treatment of an article engaged by said chuck and including a valve, a normally disabled mechanical means for actuating said valve, and means connected to said vacuum line operated by the creation of a negative pressure when an article is engaged by said chuck to enable said mechanical means to effectively function.

5. In a glass burn-off machine of the type wherein a revolving turret equipped with a row of vacuum-type article chucks is provided to convey said chucks through loading and burn-off zones, a vacuum supply line including a valve for each chuck, each valve having an operating stem one end of which carries a roller, a cam engageable by said roller only during the travel of a chuck through a loading zone to open said valve, the other end of said valve stem having a diaphragm attached thereto constituting one wall of a negative pressure chamber; and a conduit connecting said chamber with said chuck whereby, when a negative pressure is created in said line by the engagement of an article by the chuck, closure of the valve after the chuck leaves the loading zone and enters the burn-off zone is prevented.

6. In a burn-off machine, vacuum chuck, means providing a path of travel for said chuck through loading, burn-off and unloading zones respectively, a vacuum line, a valve, said valve having a first chamber and a second chamber in communication with each other, said first chamber being in communication with said chuck and normally open to atmosphere and said second chamber being in communication with said vacuum line, said valve also having an element normally closing the communication between its chambers and another element for closing said first chamber to atmosphere when the valve is operated, means for operating said valve only while said chuck is passing through the loading zone, means activated by the creation of negative pressure in said chuck when an article is engaged thereby to independently hold said valve

operated during passage of said chuck through the burn-off zone, and means for restoring said valve while said chuck is passing through the unloading zone.

7. In an article-treating machine, a vacuum-type article chuck, means for moving said chuck through loading, article-treating and unloading zones respectively, a vacuum line, a valve in communication with said chuck and providing a normally closed passage between said line and chuck and providing a normally open passage between atmosphere and said chuck, a spring holding said valve in its normal position, means for actuating said valve to open said first passage and to close the second when said chuck enters the loading zone, means activated by the creation of negative pressure in said chuck after an article is engaged thereby to hold said valve actuated independently of said valve-actuating means after said chuck leaves the loading zone and enters the article-treating zone, and means for forcing said valve closed against the action of said valve-holding means when said chuck enters the unloading zone to release the article from the chuck.

8. A machine such as defined by claim 7 including a device associated with the chuck adapted to direct a treating medium against an article engaged thereby while the chuck is passing through the article-treating zone, a supply line to said device, a normally closed valve in said supply line, an operating element normally disassociated therefrom, means activated by the creation of the negative pressure in the chuck after the article is engaged thereby for operatively associating said operating element with said latter valve, and means for actuating said element to open said latter valve when the chuck enters the article-treating zone.

9. In a burn-off machine, a vacuum article chuck, a rotary turret for conveying said chuck through article-loading, article burn-off and article-unloading zones in succession, a vacuum line to said chuck, a valve in said vacuum line having an operating stem, a spring cooperative with said stem normally holding said valve closed, a roller on one end of said stem, a cam engageable by said roller only during the travel of said chuck through the loading zone to open said valve, a negative-pressure chamber having a diaphragm constituting a wall thereof and being attached to the other end of said stem, a conduit connecting said chamber with said chuck whereby a negative pressure is created in said chamber whenever an article is engaged by said chuck to prevent closure of said valve while the chuck is passing through the burn-off zone, and a cam engagable by said roller while the chuck passes through the unloading zone to aid said spring in moving said stem to its initial position against the action of negative pressure in said negative-pressure chamber.

10. In a burn-off machine such as defined by claim 9, a burn-off burner adapted to surround an article engaged by the chuck, a fuel supply line to said burner including a spring-closed valve, an element for opening said valve, said element being normally inoperatively associated with respect to said valve, a negative pressure chamber having a diaphragm wall linked to said element and adapted to move the same into operative association with said valve whenever negative pressure is established in said chamber, a conduit establishing communication between said chamber and the chuck whereby, when an article is engaged thereby, negative pressure is

created in said latter chamber, and means for moving said element with respect to said latter valve to open it as the chuck enters the burn-off zone.

11. In a burn-off machine, a vacuum-type chuck, a turret for conveying said chuck through loading and burn-off zones, a burn-off burner, a fuel line to said burner including a spring-closed valve, an element for opening said valve, said element being normally inoperatively associated with respect to said valve, a negative-pressure chamber having a diaphragm wall linked to said element and adapted to move the same into operative association with said valve whenever negative pressure is created in said chamber, a conduit establishing communication between said chamber and the chuck whereby when an article is held engaged by said chuck, negative pressure is created in said chamber, a pivoted arm coupled to said element, 20 a roller on said arm, and a cam engageable by

said roller to move said element in a direction to operate said valve while said chuck is passing through said burn-off zone.
